WHEEL CHAIR

Reuben T. Hogg, Chicago, Ill.

Application November 30, 1949, Serial No. 6,330

Term of patent 7 years

(Cl. D15—1)

To all whom it may concern:

Be it known that I, Reuben T. Hogg, a citizen of the United States, residing at Chicago, in the county of Cook and State of Illinois, have invented a new, original, and ornamental Design for a Wheel Chair, of which the following is a specification, reference being had to the accompanying drawings forming a part thereof, in which:

Fig. 1 is a side elevation of a wheel chair showing my new design; Fig. 2 is a front elevation thereof; Fig. 3 is a plan view of the chair; Fig. 4 is a rear elevation thereof; and Fig. 5 is a perspective view of the new chair.

I claim:

The ornamental design for a wheel chair, as shown and described.

REUBEN T. HOGG.
